VIBRATING HAND TROWEL

William P. Day, John J. Day, and William P. Day, Jr., Cleveland Heights, and Vincent E. Heglaw, East Cleveland, Ohio

Application July 13, 1944, Serial No. 544,658

2 Claims.

(Cl. 94—45)

This invention relates to a hand-operated trowel for use in spreading, compressing and vibrating a layer of mortar concrete mix or the like.

One of the objects of the invention is to provide a trowel of the character described which is provided with power-operated means for imparting rapid and violent vibrations to the trowel in a plane substantially parallel with the working face of the trowel.

Another object of the invention is to provide a trowel having the above described distinguishing features and characteristics which is provided with a motor-operated vibrator unit which is carried by the trowel, the motor being shielded so as to reduce to a minimum the transmission of vibrations from the vibrator unit to the motor.

A further object of the invention is to provide a hand-operated trowel of the character described which is adapted for use in spreading, compressing and vibrating a layer of mortar or concrete mix, the vibrator unit being operated by an electric motor which is connected directly with the rotor of the vibrator, the motor being shielded against the vibrations of the vibrator unit.

A still further object of the invention is to provide a hand-operated trowel of the character described which is provided with a plurality of handles for operating the same which are formed of rubber or similar material so as to prevent the vibrations being transmitted to the operator.

Further and more limited objects of the invention will appear as the description proceeds and by reference to the accompanying drawings in which

Fig. 1 is a view in front elevation of our improved trowel;

Fig. 2 is a vertical sectional view taken on the line 2—2 of Fig. 6;

Fig. 3 is a horizontal sectional view taken on the line 3—3 of Fig. 2;

Fig. 4 is a vertical sectional view of the rotor taken on the line 4—4 of Fig. 5;

Fig. 5 is a horizontal sectional view taken on the line 5—5 of Fig. 4;

Fig. 6 is an end view in elevation of the trowel;

Fig. 7 is a transverse sectional view of an attachment for the trowel taken on the line 7—7 of Fig. 8;

Fig. 8 is a top plan view of the attachment;

Fig. 9 is a top plan view of the trowel; and

Fig. 10 is a view in end elevation of the trowel with a tool secured thereto.

Referring now to the drawings, the reference character 1 designates a casting which is pref-

erably formed of aluminum, magnesium or some similar light material. The body of the casting has therein a centrally disposed recess in which is journaled a shaft 2 to which is keyed a rotor 3 which has a counter-weighted portion 3a. The lower end of the shaft 2 is journaled in a bearing 5 carried by the body member while the upper end of the shaft is journaled in a bearing 4 carried by a closure plate 6 which is circular in shape and secured in place by bolts 7. The shaft 2 projects through an opening provided in the plate 6 which opening is closed by a plate 8 held in place by bolts 9. The plate 6 has thereon a pair of integrally formed semi-circular ribs or flanges 10. Secured to each of the semi-circular flanges 10 are a pair of semi-circular members 11 which are preferably formed of rubber or similar composition. The members 11 are secured in place by means of curved plates 12 which are held in place by bolts 13. Carried by the casting is an electric motor M having a shaft 14 which is directly connected to the shaft 2 of the rotor by means of a rubber sleeve 15. The motor M is secured to the members 11 by means of a sleeve 16 which is secured by bolts 13 and segment nuts 16a.

The rotor 3 is shown in detail in Figs. 4 and 5 and preferably consists of a casting which is provided with a counter-weighted portion 3a. Disposed on opposite sides of the rotor are a pair of plates 17 which are preferably brazed or welded thereto and shaped as shown most clearly in Fig. 4. Secured to the trowel and disposed at opposite sides thereof are a pair of angular plates 18 which are held in place by bolts 19. Secured to each of the plates 18 is a handle 20 which is provided with an opening 21 by means of which the trowel is manipulated. The handles are secured in place by a plurality of bolts 22. The front of the trowel is provided with an angularly disposed rib 23 which extends upwardly therefrom, as shown most clearly in Fig. 6. Also formed integrally with the casting are a plurality of spaced ribs 24. The working face of the trowel is flat and is disposed in the same plane as the bottom edge of the ribs 24.

It will be noted that the motor is vertically disposed and connected directly with the shaft of the rotor. The motor is adapted to be connected with a suitable source of current by means of a wire 25 and is driven at high speed of the order of 5000 to 7500 revolutions per minute. It will be noted that the rotor is journaled so as to rotate in a plane substantially parallel with the working face of the trowel so as to impart rapid

and violent vibrations thereto as the trowel is moved over the surface of the layer of mortar or mix. The trowel is adapted and intended for use in spreading and vibrating a layer of mortar or concrete mix. The trowel may be used for spreading and vibrating a layer of mix in a roadbed or sidewalk or in a wall or floor.

In Figs. 7, 8 and 10 there is disclosed an attachment for the vibrator which comprises a rod 26 which is welded to a curved plate 27 which has therein openings 29 and 30. The rod 26 may be made up of a plurality of sections, if desired, and is used to transmit vibrations to a column or form. The attachment is secured to the trowel by means of bolts 31.

It will now be clear that we have provided a vibrating trowel which will accomplish the objects of the invention as hereinbefore stated. Various changes may be made in the details of construction and arrangement of parts without departing from the spirit of our invention. The embodiment of the invention herein disclosed is to be considered merely as illustrative and not in a limiting sense as the invention is limited only in accordance with the scope of the appended claims.

Having thus described our invention, what we claim is:

1. A hand operated trowel comprising a casting having a bottom wall for smoothing cement and the like, said casting having a recess therein; a rotor, said rotor including an axle and being unbalanced about its axle, said rotor being disposed in said recess with the axle thereof extending normal to said bottom wall; a bearing in said casting for one end of said axle; a plate closing said recess, said plate having an opening therethrough; a bearing in said opening for said rotor

axle, said plate including flanges extending parallel with said axle and arcuately; a motor for driving said axle, said motor including a casing having depending arcuate flanges; an arcuate resilient member attached to each of the first-mentioned flanges and to the respective depending flanges for supporting said motor, said motor including a drive shaft in alignment with said axle; and a resilient sleeve interconnecting the drive shaft and said axle.

2. A hand operated trowel comprising a casting having a bottom wall for smoothing cement and the like, said casting having a recess therein; a rotor, said rotor including an axle and being unbalanced about its axle, said rotor being disposed in said recess with the axle thereof extending normal to said bottom wall; a bearing in said casting for one end of said axle; a plate closing said recess, said plate having an opening therethrough; a bearing in said opening for said rotor axle, said plate including flanges extending parallel with said axle and arcuately; a motor for driving said axle, said motor including a casing having depending arcuate flanges; an arcuate resilient member attached to each of the first-mentioned flanges and to the respective depending flanges for supporting said motor, said motor including a drive shaft in alignment with said axle; and a resilient sleeve interconnecting the drive shaft and said axle; and handles for said trowel comprising a pair of spaced resilient members attached at one end to said casting and projecting in a direction laterally with respect to the plane of rotation of said rotor.
